US00D570477S

(12) **United States Design Patent**
Galogly et al.

(10) **Patent No.:** **US D570,477 S**
(45) **Date of Patent:** **** Jun. 3, 2008**

(54) **MEDICAL FLUID ADAPTOR**

(75) Inventors: **Dale Marvin Galogly**, Mount Vernon, OH (US); **Theodore J. Mosler**, Raleigh, NC (US)

(73) Assignee: **Smiths Medical ASD, Inc.**, Rockland, MA (US)

(**) Term: **14 Years**

(21) Appl. No.: **29/278,289**

(22) Filed: **Mar. 23, 2007**

(51) **LOC (8) Cl.** **24-02**

(52) **U.S. Cl.** **D24/130**

(58) **Field of Classification Search** **D24/130, D24/129; 604/533-539**

See application file for complete search history.

(57) **CLAIM**

The ornamental design for a medical fluid adaptor, as shown and described.

DESCRIPTION

FIG. 1 is a perspective view of our new, original and ornamental design;

FIG. 2 is a front elevational view thereof, the rear elevational view being a mirror image thereof;

FIG. 3 is a right side elevational view thereof, the left side elevational view being a mirror image thereof;

FIG. 4 is a top plan view thereof; and,

FIG. 5 is a bottom plan view thereof.

The structure shown in phantom is for illustrative purposes only and forms no part of the claimed design.
